CLAIM

The ornamental design for a survival box, as shown and described.

DESCRIPTION

FIG. 1 is a perspective view of an embodiment of my invention;

FIG. 2 is a right side view thereof;

FIG. 3 is a top view thereof, illustrating a compass in the top of the survival box;

FIG. 4 is a left side view thereof;

FIG. 5 is a front view thereof;

FIG. 6 is a rear view thereof; and

FIG. 7 is a bottom view thereof.

FIG. 8 is a perspective view of another embodiment of my invention;

FIG. 9 is a right side view thereof;

FIG. 10 is a top view thereof;

FIG. 11 is a left side view thereof;

FIG. 12 is a front view thereof;

FIG. 13 is a rear view thereof; and,

FIG. 14 is a bottom view thereof.

The broken lines in the figures depict portions of the survival box that are included for illustrative purposes only and form no part of the claim.
